UNITED STATES PATENT OFFICE.

WILLIAM R. FORSYTH, OF SWAMPSCOTT, MASSACHUSETTS, ASSIGNOR, BY MESNE ASSIGNMENTS, TO UNITED SHOE MACHINERY COMPANY, OF PATERSON, NEW JERSEY, A CORPORATION OF NEW JERSEY.

DIE-BLOCK.

1,076,359.

Specification of Letters Patent.

Patented Oct. 21, 1913.

Application filed September 22, 1909. Serial No. 519,059.

To all whom it may concern:

Be it known that I, WILLIAM R. FORSYTH, a citizen of the United States, residing at Swampscott, in the county of Essex and State of Massachusetts, have invented certain Improvements in Die-Blocks, of which the following description, in connection with the accompanying drawings, is a specification, like reference characters on the drawings indicating like parts in the several figures.

This invention relates to die-blocks, and more particularly to sectional die-blocks comprising a plurality of parts or sections which are held together by clamping irons.

Die-blocks for use in cutting or "dying-out" material are usually constructed of a number of narrow parts or strips of hard wood, such as maple, and these strips have the grain of the wood arranged vertically and are bound together by suitable clamping irons disposed exteriorly of the die-block. Frequently each strip is composed of several sections so that the entire die-block is made up of a considerable number of small sections. It has, however, always been a difficult problem to provide suitably for the natural swelling and shrinkage of the wooden sections and the consequent expansion and contraction of the die-block within the clamping irons. Any shrinkage tends to cause cracks in the surface of the die-block and looseness between the various sections while the die-block would frequently swell enough to break the clamping irons.

Heretofore it has been customary in constructing such die-blocks to provide the clamping irons with suitable connecting portions so that the irons could be adjusted and loosened or tightened about the die-block from time to time to compensate for such expansion and contraction. This construction has been objectionable because these adjustments had to be made repeatedly and also because they could only be made after the contraction or expansion had taken place sufficiently to be noticed by the operator. Also the operator frequently neglected or forgot to make the adjustments necessary to tighten or loosen the clamping irons when needed. Thus the die-block sections might be left loose, and if then operated upon would be damaged or if too

tightly clamped and then operated upon, the clamping irons might be broken. 55

It is an object of this invention to improve and perfect die-blocks of the class described, and a particular object of the invention to provide a clamping device constructed and arranged to compensate automatically for the contraction and expansion of the die-block.

In the preferred embodiment of the invention, herein shown, one or more of the clamping members are formed of spring metal having the proper form to exert a yielding tension upon or against the sections of the die-block. When any such spring member is clamped into place contacting substantially throughout its entire length with an exterior portion of the die-block, the inward tension incident to its spring form is considerable, and is of course constant, thus automatically and instantly compensating for any expansion or contraction of the die-block sections, and maintaining the binding force of the clamping irons upon the die-block without readjustment. Preferably the clamping irons have the usual provision for adjustment of the clamping force of the irons in addition to the automatic adjusting feature above mentioned. 75 80

In the embodiment of the invention illustrated in the drawings, a rectangular sectional die-block and appropriate clamping irons having spring members arranged to contact with each end of the die-block are shown, but nothing herein contained is intended to limit the invention to the form of die-block or to the form, number or position of the spring members. 90

Other important features, combinations of parts and details of construction will herein-after be more particularly described and claimed. 95

Referring to the drawings,—Figure 1 is a view in perspective of a sectional die-block wherein a preferred form of the invention is embodied; Fig. 2 is an enlarged view, in perspective, of an end portion of a die-block 100 showing one of the spring clamping members about to be clamped in place.

In the drawings the reference character 2 indicates a plate or bed to which the die-block may be conveniently secured. Such a 105 plate would preferably be provided with a

plurality of lugs, for example 3, 4 and 5, formed upon its end and side portions to furnish means for attachment of said plate to the die-block.

5 The die-block 1 is shown as formed of a plurality of strips, 10, 11, 12, etc. each strip being composed of several sections with the grain arranged vertically, as is customary. This construction will be readily understood 10 by referring to the drawings.

The clamping irons 15, 16, 17 and 18 are arranged exteriorly of the die-block; the two side members 17 and 18 being of sufficient length to pass through suitable holes in the 15 end members 15 and 16 as shown. To bind the clamping members together and also to provide means for adjustment of the clamping force, the projecting ends of the side members 17 and 18 are threaded and 20 nuts, 20, 21, etc., are disposed thereon outside of the end members 15 and 16, so that suitable manipulation of the nuts serves to 25 adjust the clamping irons into desired position. Preferably, grooves are formed in the edges of the die-block so that the clamping irons will be countersunk or approximately flush with the edge surfaces of the die-block.

In the form of die-block herein illustrated it has been found desirable to have the 30 spring members at each end of the die-block only, accordingly the members 15 and 16 of the clamping irons are formed of spring metal and of substantially the form of the member 15 shown in Fig. 2. It will be seen 35 that as the nuts 20 and 21 are threaded onto the end portions of the members 17 and 18, the spring members 15 will be clamped into position in the groove provided therefor, as 40 illustrated in Fig. 1. When so clamped into desired position, the inward tension exerted by the spring members is considerable and is continuous, tending to force or bind the die-block sections closely together. When 45 the die-block contracts through shrinkage of the wood comprising any of the sections, or from any other cause, the action of the spring members automatically compensates for such contraction through their inward movement thus maintaining the clamping 50 irons in continuous engagement with the die-block during such contraction. The members 15 and 16 being made of spring metal will also yield outwardly and thus allow for the expansion of the die-block 55 even when said spring members are clamped "home" and thus practically straightened out against the die-block. However, it may be desirable to allow for such expansion by not clamping the spring members quite 60 "home" and thus permitting their inward spring form to allow for both contraction and expansion of the die-block.

To secure the die-block 1 to the plate 2, a series of bolts, 6, 7, 8, etc., are provided, ar-

ranged with one end to hook over the top of 65 the clamping members, and the other end to engage the lugs formed on the plate. Appropriate slots or holes in the lugs 3, 4, 5, etc., and nuts threaded onto the lower ends 70 of the bolts are herein shown although any form of engaging devices may be employed.

When the clamping members are countersunk into the edges of the die-block it may be desirable that said members be slightly 75 convexed as indicated at 13, and also that there shall be suitable spaces 14, in the die-block, to facilitate the application of the hooked ends of the securing bolts. Said spaces 14 are preferably formed on both 80 sides of the grooves wherein the clamping members lie, as it is often desirable to reverse the position of the die-block 1 so that the bottom surface may be operated upon, or to shift the die-block end for end so as to bring different portions of the same surface 85 into operation.

Having described my invention, what I claim as new and desire to secure by Letters Patent of the United States is:—

1. A rectangular die block comprising a 90 plurality of sections substantially rectangular in cross-section and of material softer than the cutting die, and means for clamping said sections together constructed and arranged to keep said sections constantly 95 under spring pressure.

2. A rectangular die block comprising a 100 plurality of sections substantially rectangular in cross-section and of material softer than the cutting die, and means for clamping said sections together comprising a spring having a bearing against one of the sides of said block and arranged to be put under tension during the clamping operation.

3. A rectangular die block comprising a 110 plurality of sections substantially rectangular in cross-section and of material softer than the cutting die, and means for clamping said sections together comprising a spring through which the clamping pressure of said clamping means is transmitted to said block.

4. A rectangular die block comprising a 115 plurality of sections substantially rectangular in cross-section and of material softer than the cutting die, and elastic means for clamping said sections together.

5. A rectangular die block comprising a 120 plurality of sections substantially rectangular in cross-section and of material softer than the cutting die, and elastic means for clamping said sections together adjustable to vary the clamping pressure.

6. A rectangular die block comprising, in 125 combination, a wooden block having the grain arranged vertically, and lateral confining means constructed to maintain said

block constantly under pressure but having provision for expansion and contraction of said block.

7. A rectangular die block comprising, in combination, a block made up of a plurality of sections substantially rectangular in cross-section and of material softer than the cutting die, and means for yieldingly clamping said sections together arranged to exert 10 its greatest pressure along a line through the middle of said block.

8. In a die block, a wooden block having the grain arranged vertically, and lateral confining means for said block comprising 15 a spring bar curved away from said block at its ends and bearing upon a side of said block in the middle line and means for bringing clamping pressure to bear upon the ends of said spring bar.

20 9. A rectangular die block comprising, in combination, a plurality of sections, and means for clamping said sections together comprising springs arranged to bear upon

said block upon opposite sides thereof and rigid connections between said springs extending along the other two sides of said block. 25

10. In a die-block comprising a plurality of sections, a plurality of clamping members arranged exteriorly of the die-block comprising rigid members and a spring member, and adjustable connections between the members to vary the tension of the spring member. 30

11. In a die-block, a plurality of clamping members comprising rigid members and spring members arranged alternately about the die-block, and adjustable means to connect a rigid member with a spring member. 35

In testimony whereof I have signed my 40 name to this specification in the presence of two subscribing witnesses.
